UNITED STATES PATENT OFFICE.

ROBERT HOSKIN, OF BROOKLYN, NEW YORK, ASSIGNOR TO CHARLES M. BAILEY, OF NEW YORK.

DESIGN FOR CARPETS.

Specification forming part of Design No. 6,329, dated December 31, 1872.

To all whom it may concern:

Be it known that I, ROBERT HOSKIN, of Brooklyn, in the county of Kings and State of New York, have invented a new and original Design for Carpets, of which the following is a specification:

The photograph illustrates my new design. This invention relates to a new ornamentation for carpets and similar fabrics, each subdivision of which is composed of a main or larger square, surrounded by four rectangular parallelograms, and joined at the corners by four smaller squares, as shown. The groundwork of the large central square and of the four smaller squares is mottled. The center of the large square contains an ornamental

rosette having a quarterfoil center, embraced by tufts of foliage and ornamental scrolls, as shown. Rosettes are also formed within the centers of the four smaller squares. The rectangles have ornamental broad borders around elongated center ornaments of mixtilinear outline, square centers, and dotted ornaments, as shown.

I claim as my invention—

The design for a carpet, composed of the several square and rectangular figures and ornaments, as shown.

ROBERT HOSKIN.
